US0D1043293S

(12) **United States Design Patent** (10) **Patent No.:** **US D1,043,293 S**
(45) **Date of Patent:** **** Sep. 24, 2024**

(54) **PRESS JAW**

(71) Applicant: **Staubli Electrical Connectors AG**,
Allschwil (CH)

(72) Inventors: **François Saugues**, Villette d'Anthon
(FR); **Dominic Bürgi**, Basel (CH)

(73) Assignee: **Stäubli Electrical Connectors AG**,
Allschwil (CH)

(**) Term: **15 Years**

(21) Appl. No.: **29/888,846**

(22) Filed: **Apr. 5, 2023**

Related U.S. Application Data

(62) Division of application No. 35/514,347, filed on Nov.
25, 2021 (U.S. filing date under 35 U.S.C. 384), and
having an international filing date of Nov. 25, 2021,
now Pat. No. Des. 1,001,604.

CLAIM

The ornamental design for a press jaw, as shown and
described.

DESCRIPTION

FIG. 1 is a front view of a press jaw, showing our new
design.

FIG. 2 is a side view thereof.

FIG. 3 is a side view thereof.

FIG. 4 is a bottom view thereof.

FIG. 5 is a top view thereof.

FIG. 6 is a back view thereof.

FIG. 7 is a perspective view thereof.

FIG. 8 is a front view of another press jaw, showing our new
design.

FIG. 9 is a side view thereof.

FIG. 10 is a side view thereof.

FIG. 11 is a bottom view thereof.

FIG. 12 is a top view thereof.

FIG. 13 is a back view thereof; and,

FIG. 14 is a perspective view thereof.

1 Claim, 14 Drawing Sheets
